TOY TYPEWRITER

Earl D. Boisselier, Glen Ellyn, Ill.

Application March 17, 1939, Serial No. 262,538

5 Claims. (Cl. 101—333)

This invention relates to toys, and more particularly to a device simulating a typewriter.

A primary object of the invention is to provide a toy which may be constructed at low cost and which will provide a source of amusement and education for juveniles for the purpose of promoting practice along the line of composing written matter after the fashion of typewriting. In that connection the invention contemplates a construction which may be made of a minimum number of parts which contributes materially to its low manufacturing cost and also its general stability in use.

A further object of the invention is to provide a toy typewriter wherein the key simulating elements are in effect individual stamps on the order of hand stamps, each bearing a suitable embossed character or other indicia, which may be individually selected by the operator and then impressed in the proper order on a sheet of paper with the aid of a guide which serves to align the printed characters in proper lineal order on the sheet.

With the foregoing and other objects in view, which will become more fully apparent as the nature of the invention is better understood, the same consists in the novel combinations and arrangements of features as will be hereinafter more fully described, illustrated in the accompanying drawing and defined in the appended claims.

A preferred and practical embodiment of the invention is shown in the accompanying drawing, in which:

35 Figure 1 is a perspective view of the device. Figure 2 is a vertical cross-sectional view thereof.

Figure 3 is a perspective view of one of the character bearing keys.

40 Figure 4 is a side elevation of the key shown in Fig. 3.

Similar reference characters designate corresponding parts throughout the several figures of the drawing.

45 As will be observed from the drawing, the toy includes in its organization a body designated generally as A and preferably made as a single stamping from lithographed metal. Said body includes the side walls 1 and the top wall 2, the latter being provided with a plurality of key receiving openings 3. The top surface may be also provided near the front with a portion 4 indicating a space bar, and may also be depressed as indicated at 5 to simulate the type bar well 50 of a standard typewriter, the type bars being

lithographed in the well. The rear portion of the top wall 2 is provided with a transverse paper slot 6 lying adjacent a platen bar or strip 7. The side walls of the body 1 also carry beneath the top wall 2, a stamp pad support 8. This support 5 consists of a suitable piece of metal having the end portions thereof bent down into parallel relation with the side walls 1—1 and suitably secured thereto by clinching, eyeletting or otherwise. The member 8 carries a felt or other surface supplied with ink which will properly provide the type key characters with ink for making impressions on the paper, as they rest in normal position.

The back of the body A is closed by a rear wall 15 designated generally as B. The ends of this wall are suitably fastened as indicated at 9 to the vertical side walls 1—1 of the body, and the upper edge thereof is off-set inwardly on an arc to provide a paper guiding wall 10. Said wall 15 20 10 has its upper edge in feeding relation to the slot 6 so that a sheet of paper resting on the wall 10 may be fed upwardly through the slot and into position to be passed rearwardly over the platen bar 7. For the purpose of manipulating 25 a sheet after the fashion of a standard typewriting sheet suitable paper feeding means designated generally as C is provided. According to the illustration, such means comprises a shaft 11 which may be a wire of suitable gauge, knurled 30 at spaced intermediate points to receive rubber sleeves 12 which frictionally bear against the paper feeding surface 10 of the back member B. The ends of the shaft 11 are suitably journaled 35 in the side walls 1—1 of the body and one end of the shaft may be provided with an operating knob 13 to enable the operator to rotate the shaft and thus feed the paper backward or forward on the surface 10.

The body A is also equipped with a pivoted or 40 swinging type-aligning bar designated generally as D. This bar includes a body 14 having a plurality of openings 15 extending in lineal order across the same and in spaced relation to determine the proper spacing of letters or characters 45 to be imprinted on the sheet. The body 14 is provided with the down-turned arms 16 which are pivoted as at 17 to the outer side walls 1 of the body. It will thus be apparent that the member D may be swung to and from operative 50 relation to the platen bar or strip 7 for the purpose of holding the paper fed through the slot 6 in position to receive impressions from the type keys.

The type elements designated generally as E 55

are intended to be inserted in and removed from the type key openings 3 previously referred to. These type keys are preferably made of light metal and include a top portion 18 having the 5 desired letter or character lithographed or otherwise placed thereon, said member 18 being carried by the body of the key which is of substantially U-shaped formation. That is to say, the body of the key consists of a leg 19 integral with 10 the top 18, a transverse web portion 20 and another leg 21 extending upwardly toward the top 18. The upper end of the leg 21 is not connected with the top 18 thereby leaving the leg 21 free to provide enough tension to frictionally hold the 15 key in its related opening 3. In other words, the body of the key element E is resilient so that it will be firmly, yet removably, held in its related key opening. The web 20 of the key is provided with an embossed letter or character 20 which is used for printing purposes.

When it is desired to use a device constructed as described, it is only necessary to swing the type guiding member D to the dotted line position shown in Fig. 2 and insert a paper sheet from 25 the rear of the unit and between the rubber feeding rollers 12 and the surface 10. By rotating the shaft 11 the paper may be thus fed upwardly through the slot 6 until the sufficient amount of sheet has progressed through the slot 30 to cover the platen bar 7. The type guiding bar D may then be pushed down to its normal or full-line position and hold the paper sheet firmly against the platen bar. The paper sheet being thus properly positioned in the device the operator 35 can then proceed to stamp the desired letters on the sheet. This is accomplished by removing the selected type key from its position on the top wall of the device and placing the end thereof having the embossed character thereon 40 through one of the openings 15 of the type guiding bar D. Since the openings 15 are properly arranged so as to give the correct space between letters the process of building up words by selecting the proper key and repeating the operation 45 just described may be continued until a complete line of letters or characters has been made on the paper sheet. When one line has been completed the knob 13 of the paper feeding means C may be turned to bring a fresh portion of the 50 paper into position to receive another line of characters.

From the foregoing it will be apparent that the present device provides a simple and practical means of assembling a series of letters to form 55 words in lineal order or using other characters, as numerals and the like, that ordinarily appear on a standard typewriter. It will of course be understood that the individual keys preferably bear letters or characters simulating a standard typewriter keyboard so that a wide range of printed matter may be developed by proper use 60 of selected keys.

Without further description it is thought that the features and advantages of the invention will 65 be readily apparent to those skilled in the art, and it will, of course, be understood that changes in the form, proportion and minor details of construction may be resorted to, without departing from the spirit of the invention and scope 70 of the appended claims.

I claim:

1. In a toy typewriter, a paper support, and a plurality of individual character bearing keys adapted to be selectively chosen for impressing characters on a paper sheet passing over said support, each of said keys comprising a metallic strip including a top having an identification character thereon and bent to form a pair of opposite leg members, one of which has its end free adjacent the top and the other of which is connected with the top thereby to provide a resilient type key body, said legs being connected by a transverse web having an embossed printing character thereon. 5

2. A toy simulating a typewriter, comprising, 15 a body including a top wall having a plurality of openings, a support below said wall and including an inking surface, a plurality of type keys removably and frictionally held in said openings and having a printing character on one end thereof, 20 a platen surface on the body and spaced from said top wall by a paper receiving slot, a back wall fitted to the body and having an inwardly and upwardly curved paper sheet supporting wall in feeding relation to said slot, a shaft having 25 friction means thereon overlying said wall for advancing a paper sheet thereover, a type alining and paper holding bar pivotally mounted on said body, said bar having a plurality of openings for receiving the character bearing end of the 30 type keys.

3. A toy simulating a typewriter, comprising, 35 a body including a top wall having a plurality of type key openings, a support below said wall and including an inking surface, a plurality of type keys 40 removably fitted in said openings and having a printing character on one end thereof, a platen surface on the body and spaced from said top wall by a paper receiving slot, a paper supporting wall in feeding relation to said slot, means 45 for advancing a paper sheet over said wall, and a type alining bar pivotally mounted on said body, said bar adapted in its lowered position to rest on said platen surface to hold the paper down and having a plurality of openings for receiving the 50 character bearing end of the type keys.

4. A toy simulating a typewriter, comprising, 55 a body including a top wall having a plurality of key receiving openings near the front portion thereof and having a platen surface near the rear thereof, a support below said top wall and including an inking surface, shiftable means having a plurality of alined openings and cooperating with the said platen surface for holding a paper sheet thereon and the openings serving as type 60 alining guides, and a plurality of type keys removably fitted in said openings of the top wall and each having a printing character on one end thereof and adapted to normally rest on said inking surface. 60

5. In a toy typewriter, a paper support, and a plurality of individual character bearing keys adapted to be selectively chosen for impressing characters on a paper sheet passing over said support, said keys each comprising a one-piece 65 metallic body bent into substantially oblong formation and having an identification character on one short end and a corresponding embossed printing character on the other short end.

EARL D. BOISSELIER. 70
